UNITED STATES PATENT OFFICE.

MONROE W. CARROLL, OF BEAUMONT, TEXAS.

ROTARY DRILL BIT.

Application filed October 14, 1920. Serial No. 416,930.

To all whom it may concern:

Be it known that I, MONROE W. CARROLL, a citizen of the United States, and residing at Beaumont, Jefferson County, State of Texas, have invented certain new and useful Improvements in Rotary Drill Bits, of which the following is a specification.

This invention relates to rotary drill bits used in sinking wells, particularly oil wells, in which the well shaft is projected downwardly through strata of various kinds and consistencies such as sand, loam and clay, water under pressure being forced downwardly by a hydraulic pump through the interior of the drill pipe, through the drill, and then passing upwardly around the drill pipe to the surface of the ground, carrying with it the cuttings which have been loosened by the cutting blades of the drill.

In drilling operations considerable difficulty has been encountered in keeping the water orifices in the drill free from obstructions, as particles of pump packing, trash and hose lining pass downwardly with the water being pumped and often clog the water orifices. It is an object of the present invention to provide means for preventing the clogging of these orifices, and this is accomplished by the addition of a straining device so positioned at the lower end of the drill pipe that no particles of matter can pass into the drill, the straining device itself being of such capacity that it cannot become clogged.

Another cause of delay and vexation in drilling operations is due to the fact that when the hydraulic pump at the top of the shaft is shut down sand and other material tends to force its way back through the water orifices and into the drill pipe. A feature of this invention resides in the provision of means for preventing this inrush of water and foreign material, an automatic valve being provided for this purpose. It is further found that breakage of the drill pipe often occurs in its lowermost section, that is, the section immediately behind the drill, and that upon withdrawal of the drill pipe the drill is left at the bottom of the well. My invention further contemplates means whereby the drill may be withdrawn with the main portion of the drill pipe even when the lowermost section of the drill pipe has been broken.

The invention will be fully disclosed in the following description when taken in

connection with the accompanying drawings in which:

Fig. 1 is a longitudinal section through the lower end of a drill pipe showing the improved drill secured thereto;

Fig. 2 is a side elevation of the drill bit partly broken away to show the automatic valve;

Fig. 3 is a section on the line 3—3 of Figure 1;

Fig. 4 is a section on the line 4—4 of Figure 1; and

Fig. 5 is a view similar to Figure 2 showing a modified form of valve.

The drill pipe is in sections, two of which 10 and 11, are illustrated in the drawings, the section 11 being the lowermost section of the pipe, to which the bit is secured. The adjacent ends of the sections are externally 75 screw threaded and are screwed into the sleeve 12 which connects them, a space being left between the adjacent ends of the pipe sections in which is positioned a ring 13 having threaded engagement with the 80 sleeve 12. The drill bit is indicated at 14, this bit having a hollow shank 15 exteriorly threaded to receive a sleeve 16 for connection to the lower pipe section 11 and interiorly threaded to receive a short tube 17 85 provided at its lower end with an annular valve seat 18. A coupling 19 has threaded engagement with the short tube 17 and with an elongated strainer 20 which extends upwardly above the ring 13 and has secured 90 to its upper end a cap 21 provided with lugs 22 by means of which it is centrally spaced within the pipe section 10.

The shank of the drill bit below the tube 17 is hollowed out to provide a chamber 23 95 for a ball valve 24 which may be of any suitable material but preferably of metal and hollow so that it will float. The chamber 23 has water outlet orifices 25 at its lower end to permit the outflow of water on 100 either side of the drill bit or cutting blade.

In the operation of the drill it is constantly rotated by power mechanism at the top of the well shaft and water is forced downwardly through the interior of the drill pipe by a hydraulic pump, the water passing through the holes in the strainer 20 and downwardly through the tube 17, forcing the float valve 24 from its seat and passing outwardly through orifices 25. It then 110 passes upwardly around the drill pipe carrying with it sand, clay, etc., loosely by the

cutting blade. The strainer prevents foreign matter, such as pump packing, hose lining, etc., from clogging up the orifices 25, the strainer being of such length and 5 having such capacity that it need only be cleaned at long intervals. Whenever the hydraulic power mechanism is shut down and the pressure within the drill pipe falls off any external pressure of fluid at the lower 10 end of the drill will serve to raise the valve 24 and prevent the entrance of such fluid and sand and other foreign matter into the interior of the drill and drill pipe.

In case the lower section 11 of the drill 15 pipe is broken in the drilling operation the drill is not lost inasmuch as it is connected to the next section 10 by means of the strainer tube 20 and cap 21, the diameter of the cap 21 across its flanges 22 being larger 20 than the inner diameter of the ring 13. When the main portion of the pipe is raised therefore the lugs 22 will rest on the ring 13 and the drill will be removed from the well.

25 If desired a solid ball valve 24' may be used instead of the hollow valve illustrated in Figure 1 and a spring 27 used to normally press this valve against its valve seat, this modification being illustrated in Figure 5.

30 Various changes may be made in the design and arrangement of the component parts of the invention which is therefore not limited in its scope to the exact forms 35 disclosed.

Having thus described my invention what I claim as new and desire to secure by Letters Patent is:—

1. A drill bit having a passage there- 40 through for fluid under pressure, said pas-

sage having an enlarged portion or chamber and an annular valve seat which faces downwardly into said chamber, and a ball valve in said chamber adapted to float upwardly against said valve seat to prevent the flow 45 of fluid through said passage in an upward direction.

2. A drill bit having a passage there- 50 through for fluid under pressure, said passage having an enlarged portion or chamber and an annular valve seat which faces downwardly into said chamber, said passage being restricted below the chamber, and a ball valve in said chamber and movable between the obstruction in the passage and the valve 55 seat and adapted to move upwardly against the valve seat to prevent the flow of fluid through said passage in an upward direction.

3. The combination with a sectional drill 60 pipe, of a drill bit secured to the end section thereof and having a portion constituting a strainer extending through said end section and into the adjacent section, and a ring positioned between the ends of said sections 65 for engaging said portion when the end section is broken, for the purpose set forth.

4. The combination with a sectional drill 70 pipe, of a drill bit secured to the end section thereof and having a portion constituting a strainer extending through said end section and into the adjacent section, the end of said portion being enlarged, and a ring of smaller inside diameter than the diameter 75 of the enlarged end of said portion secured between the ends of said sections for engaging said portion when the end section is broken, for the purpose set forth.

In testimony whereof I affix my signature.
MONROE W. CARROLL.
